(57) **CLAIM**

I claim the ornamental design for a waterfowl decoy accessory, substantially as shown and described.

DESCRIPTION

FIG. 1 is a top, front, right side perspective view showing my new design of a waterfowl decoy accessory;

FIG. 2 is a rear view thereof;

FIG. 3 is a front view thereof;

FIG. 4 is right side view thereof;

FIG. 5 is a left side view thereof; and,

FIG. 6 is a top view thereof.

The broken lines shown in the drawings depict portions of the waterfowl decoy accessory that form no part of the claimed design.
